UNITED STATES PATENT OFFICE.

SAMUEL MCFARLAND, OF COATESVILLE, PENNSYLVANIA.

CASTING APPARATUS.

1,418,949.

Specification of Letters Patent. Patented June 6, 1922.

Application filed January 13, 1920. Serial No. 351,239.

To all whom it may concern:

Be it known that I, SAMUEL MCFARLAND, a citizen of the United States, residing in Coatesville, in the county of Chester and 5 State of Pennsylvania, have invented a certain new and useful Improvement in Casting Apparatus, whereof the following is a specification, reference being had to the accompanying drawings.

10 My invention relates particularly to what are known as bottom sprue plates for ingot molds.

It is the ordinary practice to arrange such molds in groups to facilitate the pouring 15 of molten metal into them and, ordinarily, each such pouring group of such molds is supported upon a single bottom sprue plate, conveniently formed of a single, substantially square, iron casting; which single 20 plate includes means arranged to direct the molten metal to all of the molds in the group. For instance, a single iron casting approximately nine feet square and nine inches thick is ordinarily employed as the 25 bottom sprue plate for a group of four molds for ingots twenty-one inches square; said molds being grouped in symmetrical relation with the four corners of said plate. The cost of such a single cast plate is in 30 excess of eight hundred dollars, and if it is broken in any part, the entire plate becomes worthless and must be discarded.

Therefore, it is an object of my invention to provide a bottom sprue plate adapted to 35 support a pouring group of ingot molds by forming the bottom sprue plate in sections which are respectively local to the individual molds but have means in common arranged to direct molten metal to all the molds 40 in the group simultaneously; for instance, such means may include a single runner conduit common to all of said molds, and complementary channels in said separable sections, cooperatively arranged to direct 45 molten metal from one to another.

I am aware that it is old to provide the individual molds of a pouring group with individually separable drag plates; for instance, such structures as are shown in Ireland's British Letters Patent No. 263 dated 50 January 23, 1873 and in Healey's British Letters Patent No. 1788 dated May 16, 1873, and also indicated in Griffith's Letters Patent of the United States No. 644,740 granted 55 March 6, 1900. But it is characteristic of

those structures that they have a single unitary bottom sprue plate common to the whole group of drag plates and molds which are supported by said single bottom plate and, consequently, have the disadvantages 60 above contemplated, incident to any breakage of such a bottom plate. Therefore, my present invention is distinguished from those structures of the prior art as above described, and I disclaim the disclosures of 65 said Letters Patent.

My invention includes the various novel features of construction and arrangement hereinafter more definitely specified.

In said drawings; Fig. I is a plan view of 70 a convenient embodiment of my invention adapted to cooperate with a pouring group of eight ingot molds having a common, and centrally vertically disposed, runner conduit, through which molten metal may be 75 poured into all of said molds contemporaneously.

Fig. II is a vertical sectional view, taken on the line II, II in Fig. I, and showing 80 said central vertical runner.

Fig. III shows a modified, and simpler, form of my invention, adapted to cooperate with a pouring group of four ingot molds.

Referring to the form of my invention shown in Figs. I and II; eight ingot molds 85 1 are arranged in a pouring group surrounding the central vertical runner 2; so that molten metal poured into the latter is directed to all of said molds simultaneously. As indicated in Fig. II; each of said molds 90 1 is a substantially straight vertically disposed tube, primarily open at top and bottom; but each mold is closed at the bottom by resting upon a sectional sprue plate which is local to it but cooperatively related to the other molds in the group.

Said central runner 2 has the vertical passageway 3 for molten metal and is supported by the central plate section 4 which has the central recess 5 for the central brick 100 6 which has the central opening 7 registering with said passageway 3 in said runner. Said plate section 4 also has four radial channels 9 respectively lined with bricks 10 having flanges 11 fitted into said central 105 brick 6 and enclosing passageways 12 for molten metal thus radiating from said central runner 2. The circular series of four molds 1, immediately adjoining said central runner 2, are supported upon the series of 110

- four sectional bottom sprue plates 14, one of which is local to each of said molds. Said plate sections 14 are each separable from said plate section 4 but are conveniently fitted in the grouped relation shown, by the interlocking engagement of flanges 15 on said central plate 4 between flanges 17 on said plates 14; whereby said sections 14 are normally held in cooperative relation, in the same plane. Each of said plate sections 14 has a channel 18, extending radially with respect to said runner 2 and lined with refractory brick 20 enclosing passageway 21 for molten metal. Each of said bricks 20 has a flange 23 fitted to the adjacent brick 10, so as to cooperate therewith to direct molten metal therethrough, and each of said bricks 20 has a nozzle slot 25 arranged to direct the molten metal therefrom into the mold 1 surrounding said brick 20 and resting upon the respective sectional sprue plate 14. Moreover, the channel 18 in each of said sectional sprue plates 14 also contains a brick 27 enclosing the passage 28 for molten metal and having the flange 29 fitted to said brick 20 so as to cooperate with the latter in directing the flow of molten metal therethrough, to the outer circular series of four molds 1 which are respectively mounted upon sectional bottom sprue plates 32 which are separable from said sectional plates 14 but are conveniently fitted in the grouped relation shown by the engagement of the outer ends of said plates 14 in recesses 34 in said plates 32. Said plate sections 32 have channels 35 in which said bricks 27 extend from said plate sections 14, and said bricks have flanges 36 fitted in recesses 37 in the bricks 38 which are held in recesses 40 in said plate sections 32 and enclose passageways 41 in communication with nozzle slots 42 through which the molten metal is directed to the molds 1 which rest upon said plate sections 32.
- Therefore, it is to be understood that the construction and arrangement above described are such that although each of said molds 1 has a sectional bottom sprue plate which is separable from the bottom sprue plates of the other molds; yet, said sections are so cooperatively connected and related as to form an integral structure whereby all of the molds in the pouring group they support may be filled at one pouring of molten metal directed thereto through said central runner 2.
- Of course, the sectional structure shown in Figs. I and II is adapted for use with groups of different numbers of molds. For instance, the outer series of four molds 1 may be omitted and the passageways for molten metal radiating from said central runner 2 terminated with said bricks 20, so that the remaining structure is adapted to simultaneously direct the molten metal only to the inner series of four molds. Other variations may be effected as may be convenient in reference to the number of molds and the space in which they are to be grouped. For instance, any of the sections 14, with its appurtenant section 32, may be omitted, and the passageway leading thereto shut off at the central section 4. For instance, as shown in Fig. III; two oppositely counter-part bottom plate sections 45 may have their adjacent ends recessed as indicated at 46 to receive a central brick 47, adapted to cooperate with such a central runner as indicated at 2, and each of said sections 45 may have a channel 48 lined with bricks 49, 50 and 51, each of the latter having a nozzle slot 52 through which molten metal is directed to the mold 53 supported by the respective plate section 45. Moreover, the abutting inner ends of said sections 45 may have oppositely counter-part recesses 55 forming a channel lined with bricks 56 to direct molten metal from said central brick 47 through bricks 58 and 59, by way of the nozzle slots 60 in the latter, into molds 70 supported upon sectional bottom sprue plates 71 having channels 72 in which the latter bricks extend.
- Of course, the structure shown in Fig. III is also susceptible of variation. For instance, either or both of said plate sections 71 may be omitted, to suit the convenience of the operator, and the space in which the casting operation is to be performed.
- The construction and arrangement above described has numerous advantages as compared with the single unitary bottom sprue plate heretofore ordinarily employed. For instance, considered in the order in which said advantages appear, much smaller and consequently, less costly, patterns may be used to form the series of plate sections which are counterparts of each other; such sections are more readily manipulated than the single larger plate aforesaid; they may be arranged in groups of differing numbers, whereas, no such variation is possible with the single unitary plate; and, if the bottom sprue plate structure shown in Fig. I, considered as a whole, is broken in any part, only that sectional part in which the break occurs, is lost, and may be immediately replaced by another similar sectional part, not only without such loss as is incident to the breakage of the unitary plate aforesaid, but without loss of time in the casting operation. That is to say, with reference to the last named advantage, that damage to any section of my improved structure aforesaid may be repaired without disturbing the other portions thereof and, consequently, without loss of time theretofore expended in assembling such other portions in cooperative relation with the molds.
- It may be observed that it is characteristic

of each of the structures above described, that adjoining plate sections have respective channels which are complementary to form a passageway for molten metal, and it is to be noted that certain of the refractory elements which line said channels, as exemplified by the bricks above described, bridge the joints between the plate sections which include such complementary channels. Moreover, I find it convenient to so proportion and arrange the structure that the molds may overlap such joints, for instance, the joints between the central plate 4 and the plates 14 which are radially connected therewith, as shown in Fig. I, and said molds may similarly overlap the joints between the refractory elements as shown in Fig. I by the molds which rest upon the plates 32 and also shown by the molds in Fig. III. However, although such features of construction and arrangement are advantageous in that they integrate and stabilize the sectional structures described, I do not desire to limit all of my claims thereto.

Therefore, I do not desire to limit myself to the specific details of construction and arrangement of my invention herein set forth, as it is obvious that various modifications may be made therein, without departing from the essential features of my invention as defined in the appended claims.

I claim:

1. In casting apparatus; a bottom sprue plate for a plurality of ingot molds arranged in a single pouring group, including separable sections respectively local to the individual molds, a central section, independent of but cooperatively connected with said other sections and constructed and arranged to receive molten metal and direct it to said other sections; said sections extending in a common plane and having complementary channels for the passage of molten metal to said molds; and elements of refractory material in said channels, bridging the joints between said sections, and forming passageways for the molten metal; certain of said refractory elements having nozzle openings arranged to register with the respective molds mounted upon the respective sections; and a single runner conduit common to all of said molds.
2. In casting apparatus; a bottom sprue plate for a plurality of ingot molds arranged in a single pouring group, including separable sections respectively local to the individual molds, a central section, cooperatively connected with said other sections and constructed and arranged to receive molten metal and direct it to said other sections; said sections extending in a common plane and having complementary channels for the passage of molten metal to said molds; and elements of refractory material in said channels, bridging the joints between said sections, and forming passageways for the molten metal.
3. In casting apparatus; a bottom sprue plate for a plurality of ingot molds, including separable sections respectively local to the individual molds, and a central section, cooperatively connected with said other sections, extending in the same plane with said other sections and constructed and arranged to receive molten metal and direct it to said other sections; said sections having complementary channels for the passage of molten metal to said molds.
4. In casting apparatus; the combination with a central plate having an inlet for molten metal and a plurality of outlets for the same; of a series of separable plates, independent of said central plate, having means arranged for cooperative connection with said central plate, including channels for molten metal adapted to register with the outlets in said central plate.
5. In casting apparatus; the combination with a bottom sprue plate formed of separable sections; of a mold, separable from said plate, having a wall bridging a joint between said plate sections.
6. In casting apparatus; a bottom sprue plate for a plurality of ingot molds, arranged in a single pouring group, including separable sections respectively local to the individual molds, a central section independent of, but cooperatively connected with, said other sections and constructed and arranged to receive molten metal and direct it to said other sections; said sections extending in a common plane and having complementary channels for the passage of molten metal to said molds; and elements of refractory material in said channels forming passageways for the molten metal; certain of said refractory elements having nozzle openings arranged to register with the respective molds mounted upon the respective sections; and a single runner conduit common to all of said molds.
7. In casting apparatus; a bottom sprue plate for a plurality of ingot molds, arranged in a single pouring group, including separable sections respectively local to the individual molds; a central section, cooperatively connected with said other sections, and constructed and arranged to receive molten metal and direct it to other sections; said sections extending in a common plane and having complementary channels for the passage of molten metal to said molds; and elements of refractory material in said channels, forming passageways for the molten metal.
8. In casting apparatus; a bottom sprue plate for a plurality of ingot molds including separable sections respectively local to the individual molds, and extending in the same plane; said sections having complementary channels for the passage of molten metal to said molds; and elements of refractory material in said channels, bridging the joints between said sections, and forming passageways for the molten metal.

channels for the passage of molten metal to said molds from one of said sections to another.

9. In casting apparatus; a bottom sprue plate for a plurality of ingot molds, arranged in a single pouring group including separable sections, extending in a common plane; complementary pouring channels in said sections; one of said sections having a laterally 10 extending projection engaging the adjoining section; whereby, said channels may be registered, in cooperative relation.

10. In casting apparatus; a plurality of separable bottom sprue plates, extending in 15 a common plane, each adapted to support a single ingot mold and having a channel arranged to direct molten metal to such mold from an edge of the respective plate; said channels in the respective plates being complementary to each other; each of said plates having means to detachably engage an adjoining plate with said channels in registry with each other; whereby said plates may be assembled in a pouring group, in said common plane, so that molten metal may be conveyed through said channels from one plate 20 25

to another; but so constructed and arranged that each of said plates is independent of the other plates and may be removed and replaced without disturbance of the other 30 plates.

11. In casting apparatus; a bottom sprue plate adapted to support a single ingot mold, independently of other molds, with said plate extending in a horizontal plane; said plate 35 having a channel, extending from an edge thereof, arranged to conduct molten metal to such mold; said section having at its edge from which said channel extends, means arranged to independently register with another sprue plate having a complementary channel; such registering means being separable by movement of either of said plates, in its plane, without disturbance of the other plate. 40 45

In testimony whereof I have hereunto signed my name at Coatesville, Pennsylvania, this 24th day of November, 1919.

SAMUEL McFARLAND.
